Inventor:

Moses F. Carr.

Englewood, Bronx, New York,
Attys.

UNITED STATES PATENT OFFICE.

MOSES F. CARR, OF NEWTON, MASSACHUSETTS, ASSIGNOR TO CARR FASTENER COMPANY, OF CAMBRIDGE, MASSACHUSETTS, A CORPORATION OF MAINE.

FASTENER.

1,300,587.

Specification of Letters Patent. Patented Apr. 15, 1919.

Application filed December 8, 1917. Serial No. 206,830.

To all whom it may concern:

Be it known that I, MOSES F. CARR, a citizen of the United States, and a resident of Newton, in the county of Middlesex, Commonwealth of Massachusetts, (whose post-office address is care of Carr Fastener Company, Cambridge, Massachusetts,) have invented an Improvement in Fasteners, of which the following description, in connection with the accompanying drawings, is a specification, like characters on the drawings representing like parts.

This invention pertains to improvements in fasteners, and more particularly, though not exclusively, to improvements in separable fasteners for automobile curtains wherein the stud is adapted to be attached to the curtain and the socket to be carried in a recess in the automobile body, the exterior surface of the socket preferably being substantially flush with the exterior surface of the body.

In the drawings:—

Figure 1 is a front elevation of a preferred form of my invention;

Fig. 2 is a sectional elevation thereof on the line 2—2 of Fig. 1; and

Fig. 3 is a section on the line 3—3 of Fig. 2.

In the illustrative embodiment of my invention shown in the drawings, I have provided the stud 4 attached to the curtain 5 of an automobile, and projecting inwardly therefrom for engagement with a socket 6 fastened in the side of the car 7 preferably by screw-threads 8, as shown. The stud 4 is preferably provided with grooves 6' and 7', one of which is preferably adapted to engage with a preferably annular resilient

jaw 9 in the front of the socket 6, and the other of which is adapted to engage with projecting means typified by the annular ring 10 located near the back of the socket. The stud 6 may be attached to the curtain 5 in any suitable way, but I prefer to attach it by the screw-threaded stud 11 passing through the curtain and adapted to engage a knob or button 12 exterior to the curtain. The head 13 of the stud 4 is preferably rounded on the edges so that when the stud is to be entered in the socket, the annular jaw 9 will be forced outwardly so that it can pass over the stud 4. Similarly, the interior shoulder of the groove 7' is preferably rounded so that as the stud is entered in the

socket the passage of the groove 7' of the stud past the jaw 9 will not prevent the full entrance of the stud in the socket. When the stud is completely entered in the socket, as shown, the jaw 9 rests in the groove 6' and the annular projection 10 is opposite the groove 7' so that, if pressure is exerted outwardly on the curtain in any non-axial direction, the projection 10 will engage the shoulder provided by the groove 7' and head 13, thus preventing accidental withdrawal of the stud from the socket. When, on the other hand, the stud is directly withdrawn from the socket, the head 13 can pass through the projecting means 10 without engagement with the shoulder. If the stud is for any reason accidentally partially withdrawn from the socket, the spring jaw 9 will engage the groove 7', thus providing one form of double locking means, or means for yieldingly holding the stud and socket in a plurality of determined positions.

While I have shown and described a preferred form of one embodiment of my invention, it will be understood that changes involving omission, substitution, alteration and reversal of parts, and even changes in the mode of operation, may be made without departing from the scope of my invention, which is best defined in the following claims.

Claims:

1. A separable fastener comprising, in combination, a stud providing a plurality of grooves, and a socket adapted to receive said stud providing a resilient jaw element adjacent the entrance portion thereof for engagement with one of said grooves, and unyielding projection means further removed from the entrance of said socket and said resilient jaw, said unyielding projecting means being adapted to enter the second groove in said stud when the stud is tipped relative to the socket, while permitting withdrawal of said stud from said socket without engagement of said second groove by said unyielding projecting means.

2. A separable fastener comprising, in combination, a stud providing a plurality of grooves; a socket adapted to receive said stud comprising a tubular shell having a groove interiorly thereof adjacent the entrance end thereof, an annular spring in said groove, said spring engaging one of the grooves in said stud, and means interiorly of said shell and located a substantial distance

from said spring for engagement with a second groove in said stud.

3. A separable fastener comprising, in combination, a stud providing a plurality of grooves; a socket adapted to receive said stud comprising a tubular shell having a groove interiorly thereof adjacent the entrance end thereof, an annular spring in said

groove, said spring engaging one of the grooves in said stud, and unyielding means 10 interiorly of said shell and located a substantial distance from said spring for engagement with a second groove in said stud.

In testimony whereof, I have signed my name to this specification.

MOSES F. CARR.
